UNITED STATES PATENT OFFICE.

FELIX SAMSON, OF NEW YORK, N. Y.

DESIGN FOR THE NAP-SURFACE OF CLOTH.

SPECIFICATION forming part of Design No. 12,929, dated May 16, 1882.

Application filed February 25, 1882. Term of patent 3½ years.

To all whom it may concern:

Be it known that I, FELIX SAMSON, a citizen of the United States, residing at New York, in the county and State of New York, 5 have originated and produced a novel Design for the Nap-Surface of Cloths, of which the following, taken in connection with the accompanying drawing, is a full, clear, and exact description.

10 My present design refers to that class of ornamentation for cloths for which certain Letters Patent have already been granted to me, numbered respectively 12,176, 12,184, and 12,519, in which the design or figure displayed 15 on the surface is outlined by sharp, clearly-defined lines or grooves cut into the pile or nap during the operation of shearing the same.

My present design consists of a novel arrangement and combination of certain lines or 20 grooves with dots or depressions, by which a novel and striking figured effect is produced on the face of the cloth, as will be hereinafter set forth.

In the annexed drawing is represented a 25 face view of a piece of cloth embodying my present design.

The ground of the design consists of the plain, smoothly-finished nap-surface of the cloth, and the pattern or figure is outlined or 30 indicated by sharp, well-defined cuts or incisions made in the nap or pile of the fabric during the operation of shearing the same.

In the present instance the general design consists of stripes running lengthwise of the 35 cloth, the characteristic features of which are diagonal lines and dots arbitrarily arranged and combined to produce alternate bands or stripes composed wholly of dots and diagonal lines.

40 In the accompanying drawing, *a a* are short

lines of equal length running diagonally and parallel to each other, and so as to form a band or stripe, *b*, lengthwise of the cloth. This series of diagonal lines or grooves is formed, as above stated, by cutting into the nap or pile, 45 leaving the nap standing in relief between the lines. The diagonal lines *a a* are disposed at uniform distances apart along the cloth, and the length of the lines regulates the width of the stripe. The band or stripe *b*, composed of 50 diagonal lines, alternates with a band or stripe, *c*, which is composed of a series of dots or depressions cut into the nap-surface and disposed lengthwise in uniform rows *d d*, thereby forming a band or stripe of dots running 55 lengthwise and parallel with the diagonally-lined stripe.

I have shown in the present design but three rows of dots in a single stripe; but the specified number of rows is not essential to the 60 effectiveness of my design; nor is it essential that the same uniformity in dots should always be preserved in striping the surface of the fabric.

I have described the figure or design as being engraved or cut into the nap or pile on the face of the fabric; but while this method is preferable and produces the most striking results, I do not limit myself to this mode of production.

70 What I claim is—

The specified design for the nap-surface of cloths, consisting of bands or stripes of diagonal lines alternating with bands or stripes of dots, substantially as herein shown and described.

75 FELIX SAMSON.
